UNITED STATES PATENT OFFICE.

FRANK H. BOLTE, OF MILWAUKEE, WISCONSIN.

TYPE-WRITING MACHINE.

SPECIFICATION forming part of Letters Patent No. 452,335, dated May 12, 1891.

Application filed January 27, 1888. Serial No. 262,156. (No model.)

To all whom it may concern:

Be it known that I, FRANK H. BOLTE, of Milwaukee, in the county of Milwaukee and State of Wisconsin, have invented new and 5 useful Improvements in Type-Writing Machines; and I do hereby declare the following to be a full, clear, and exact description of said invention, reference being had to the accompanying drawings, and to the letters or figures of reference marked thereon, which form 10 a part of this specification.

My invention, to be hereinafter distinctly claimed, relates to the form, construction, and arrangement of the various parts of my device and to the combination of those parts 15 in groups and in one entire machine.

In the drawings, Figure 1 is a plan of my improved type-writer. Fig. 2 is an elevation of that end of the machine at the top of the 20 sheet in Fig. 1. Fig. 3 is a vertical transverse section on line X X of Fig. 1. Fig. 4 is a detail of the key-lever and type-bar and their attachments. Fig. 5 is a detail of the bracket that supports the key-lever and type-bar. Fig. 25 6 is a rear elevation of the complete type-writer. Fig. 7 is a detail of the mechanism for raising and lowering the bank of keys and their supporting-frame. Fig. 8 is a detail of that portion of the carriage-moving mechanism which is beneath the bed of the type-writer. Fig. 9 is a detail of a portion of that 30 part of the mechanism for moving the carriage and reciprocating the ink-ribbon that is above the bed of the machine. Fig. 10 is a detail showing in section the manner of pivoting a type-bar in its supporting-bracket.

The same letters and figures refer to like parts in all the drawings.

The bed of the machine A, which is a horizontal level table, is supported on the short rubber legs or feet B B. Upon the bed is supported the carriage C, which has a movement laterally in ways on the bed. In the top of this carriage and as a part of it is the paper-holding table D, which has a reciprocating movement endwise at right angles to the movement of the carriage C on the bed of the machine. Above the carriage C is a frame E, supporting the bank of type-writing keys.

On the under side of the bed of the machine a lever-arm 1 is pivoted at one end to the bed of the machine, and at the other end is attached

to the carriage C by and through the connecting-rod 2 and post 3, which connecting-rod is pivoted at one end to the lever-arm 1 and at 55 the other end to the post 3, the post 3 being rigid to the carriage C. A slot 4 is provided in the bed A, through which the post 3 passes and in which it has its reciprocal movement on the carriage. A helical spring 5 about 60 the pivot, that secures the arm 1 to the bed A, is attached at one end to the bed A and at the other end to the arm 1, and is adapted by its recoil to move the carriage on the bed from right to left as the type-writer 65 progresses. A toothed rack 6, located at the rear of the bed of the machine, is attached rigidly to the carriage C, and a weighted dog 7, secured rigidly to the rock-shaft 8, is adapted to engage alternately with 70 the rack 6 and with the rack 9, which rack 9 is supported and has a slight endwise movement on the rack 6. The rack 9 is supported on the rack 6 by means of the headed bolts or screws 10, passing through slots in the rack 75 9 and turning into the rack 6. A small coiled wire spring 11 in a recess in the rack 6 and attached at one end to the rack 6 and at the other end to the rack 9 is adapted to carry the rack 9 forward with reference to the rack 80 6 toward the left in the same direction that the carriage is moved by the helical spring 5. A set-screw 12, turning through a lug in the end of the rack 6, is adapted at its inner end to receive the thrust of a lug or cushion 13 on 85 the rack 9, and this set-screw 12 may be adjusted in or out, whereby the reciprocal movement of the rack 9 with reference to the rack 6 may be adjusted and limited. The carriage C is supported at its front and rear ends by 90 the wheels 14 14, journaled on lugs rigid to the carriage, which wheels travel on ways 15 15 on the bed A, which ways 15 15 extend across the bed laterally at its front and rear edges. The table D, which forms the top of the carriage, is preferably constructed of sheet-steel, and is secured movably to the frame of the carriage by having its lateral edges turned 95 downwardly and reversed, as shown at 16 16, forming grooves adapted to receive the flanges 100 or guides 17 17 on the frame of the carriage, which form ways whereon the table D is guided in its movement toward the front and rear endwise on the carriage. A bell-crank-

lever arm 18 is pivoted at its angle to the frame of the carriage C and is provided with a pawl pivoted to the outer end of one arm of the bell-crank, the free end of which pawl 5 is adapted to engage with the series of teeth 20 on the edge of the table D. A straight spring 21, secured rigidly in a pin 22, rigid in the arm of the bell-crank 18 and bearing against a pin 23 in the pawl 19, is adapted to 10 throw the pawl into engagement with the teeth 20 on the table D and by its recoil when the pawl is in engagement with the table D to throw the outer arm of the bell-crank 18 back against the adjusting-stop 24. The adjusting-stop 24 is pivoted to the frame of the carrier eccentrically, so that when it is in the position shown in Fig. 1 the bell-crank in 15 swinging back against it will draw the pawl 19 rearwardly only so far as is sufficient to allow it to engage with the tooth 20 next succeeding the one with which it was last in engagement; but when the adjusting-stop 24 is 20 swung around to the left, presenting its other face to the bell-crank arm 18, the bell-crank arm will then in swinging back against the stop 24 move far enough to draw the pawl 19 back into engagement with the second tooth 20 from the tooth with which it was last in engagement, whereby by throwing the bell-crank forward again the table D is moved rearwardly a distance equal to the distance apart 25 of two of the teeth 20. It will be understood that this bell-crank device and its allied mechanism is intended and adapted for moving the table D rearwardly to the extent of one or two notches, as desired, after writing 30 each line across the paper.

A clip 25 is secured to a rock-shaft 26, having its bearings in lugs at the left side of the carriage, the free edge of which clip bears 35 downward upon the table D, and is intended and adapted for receiving thereunder and clasping the paper upon the table D. A wire spring 27, coiled about the rock-shaft 26 and secured at one end to the rock-shaft and at 40 the other end to the carriage, is adapted to force the clip down yieldingly toward or upon the table D, and a thumb-latch 28, rigid to the shaft 26, is adapted for raising the clip 45 25, and also as a convenient knob for moving the table forward on the carriage. The frame E, which supports the bank of keys and the type-operating mechanism, is located centrally over the bed of the machine and above 50 the carriage and is supported movably vertically and adjustably upon and with reference to the bed of the machine.

For supporting the frame E, two standards 55 29 29 are secured, one at each end of the bed-plate and near the rear to the bed-plate, by means of a pin or screw 30 passing through the standard and turning into or fixed rigidly in the bed-plate, on which pin or screw 30 the standard is adapted to swing rearwardly 60 65 when it is desired to raise the frame E to some distance away from the carriage C, and the standard is secured in an upright posi-

tion by means of a thumb-screw 31, turning through a recess in the foot of the standard into the bed-plate, whereby, when the standard is in a vertical position, by turning down the set-screw upon it the standard is held rigidly in place, and when the thumb-screw is released the standard may be tilted rearwardly. Two arms 32 32, one at each end of the frame E and integral therewith, project rearwardly therefrom and are secured pivotally by the pins or screws 33 33 to brackets 34 34, which brackets are each provided with a recess for the reception of the standard 29, 70 75 80 85 90 95 100 105 110 115 120 125 130 said brackets being supported and having a vertical movement on said standards. An arm 35, projecting rearwardly from each of the brackets 34 34, is provided with an adjustment-screw 36, turning therethrough and bearing at its end against the projecting rear end of the arm 32, whereby the frame E is held against tipping downwardly, but is allowed to be tilted upwardly to a certain extent, an additional tilting motion of the frame 125 E in the same direction being provided for by the means described for tilting the standards 29 29. The standards 29 29 are each provided on one vertical edge with a rack adapted to mesh with a pinion 38, rigid on shaft 39, which shaft is journaled in the brackets 34. The pinions 38 38 are each let into a recess in the bracket, so as to come in front of the standard 29. At one end the shaft 39 is provided with a rigid ratchet-wheel 40, and a pawl 41, pivoted on the frame, is adapted to engage the ratchet-wheel and lock the shaft against rotating while in engagement. A small crank 42, rigid on the shaft 39, is adapted for rotating it. The object of this mechanism for raising or lowering the frame E, which supports the bank-keys, is to permit of inserting a sheet of thick material or even a block of many leaves of material, or a book, if desired, on the table 130 beneath the frame E for printing thereon.

The frame E is constructed in a semicircular form having a central semicircular area or open space, about which is arranged a series of type-bars 43 43, each of which carries 115 a type 44 in its free upper end, which type-bars are so located and pivoted about the central space that when thrown forward individually each type strikes the table D or the thereon supported material for receiving the 120 impression at the center point or axis of the circular frame E. The type-bars 43 are each pivoted at its lower end in the foot of the bracket 45, which bracket is rigidly secured to the frame E. A bell-crank key-lever 46 is 125 pivoted at its angle in the upper part of the bracket 45, and a segmental rack 47 at the end of its lower arm meshes with a segmental pinion 48, integral with the type-bar 43, whereby by depressing the outer end of the upper 130 arm of the key-lever 46 the type-bar 43 will be thrown down forwardly. A short post 49 projects upward from the outer end of the upper arm of each key-lever 46 and carries a

disk or key 50 at its top, which, for convenience, is marked with the letter, figure, or character corresponding with the letter, figure, or character in the end of the type-bar 43 operated by the particular key-lever so indicated. The radial length of the segmental arm of the key-lever and the radial length of the segmental pinion on the type-bar bear such proportions to each other that a very slight depression of the outer end of the upper arm of the key-lever will throw the type-bar down through an arc of ninety degrees or more upon the table D, and the slight elevation of the outer end of the arm of the key-lever 46 will elevate the type-bar 43 again to the vertical position. The upper arm of the key-lever 46 is held yieldingly up in the position shown in Fig. 4 by the coiled wire spring 51 inserted between it and the foot of the bracket 45. This spring 51 is preferably supported and held in position by a central pin 52, projecting rigidly from the foot of the bracket 45. The post 49 is connected to the key-lever 46 pivotally, and, passing through an aperture in the key-board 53, is guided in its movements vertically thereby.

To provide means for moving the carriage forward automatically while printing a line or spacing the words, an arm 54, provided with bifurcate free ends, which in curved form extend entirely around beneath the upper arms of all the key-levers 46, is also provided with a T-head 55, which at its outer ends is pivoted, respectively, to the parallel bars 56 and 57, which bars 56 and 57 at their other ends are hinged to the upright 58, which upright 58 is secured rigidly to a projecting-arm 59, integral with the lower part of the frame E. The free ends of the arm 54 are each provided with an upright 60, having at its top a horizontal finger-plate or spacing-key 61, adapted to receive the pressure from the hand for forcing down the arm 54 and moving the carriage forward laterally in connection with mechanism to be described. The arm 56 is connected by the thereto-jointed rod 62 with the lever-arm 63, which lever-arm 63 is pivoted and supported on the bracket 64, rigid on the frame E. The outer end of the lever-arm 63 is provided with a thereto-pivoted upright 65, which upright is provided with a series of teeth 66, adapted to engage with a projecting arm 67, rigid on the rocking-lever shaft 68. The upright 65 passes up alongside the end of the arm 67 and through an eccentric slot 69 in the cam-lever 70, which cam-lever is pivoted on the arm 67 and is adapted by its oscillation to throw the upright into or out of engagement with the arm 67, whereby the relative position of the upright 65 to the arm 67 may be adjusted, as desired, which adjustment is necessary to be made when the frame E is elevated or lowered by the means and as hereinbefore described. The rocking-lever shaft 68 is journaled at its respective ends in the upper part of the standards 29 29, and is provided at one end with the thereto-rigid

lever-arm 71, the outer end of which lever-arm is connected by the rod 72 to the outer end of the lever-arm 73, rigid on the rock-shaft 8. A spring 74, made rigid to the upright 58, bears against the bar 56 and holds it and the mechanism thereto attached yieldingly up to its highest point of movement, which is the horizontal position shown in Fig. 75. A downwardly-projecting arm 75, integral with the lever-arm 63, is connected at its lower end with a forwardly-extending arm 76, which arm 76 at its front end is bifurcate and is provided with fingers 77 77, adapted to receive and hold loosely the ink-ribbon 78, and by its reciprocation forward and back to throw the ink-ribbon immediately beneath the type as it comes down and to withdraw it rearwardly as the type is lifted therefrom. It will be seen that by the depression of the arm 54 by bearing down on the space-key 61 or by the thrust downward of the upper arm of a key-lever 46 when a letter-key is struck and by the elevation of this arm 54 by the spring 74 the rocking-lever shaft 68 and the rock-shaft 8 will be oscillated, whereby the gravity-pawl 7 will be thrust into engagement alternately with the racks 6 and 9, and the carriage in the meantime between such alternate engagement will be moved forward by the power of the helical spring 5. Ribbon-carrying reels, one at each side of the machine, having an axle 79, a crank-arm 80, a spring 81, a ribbon-spool 82, and a ratchet-wheel 83 are supported and carried on the frame E. The axle 79 is journaled in brackets integral with the frame E, and the spring 81 is coiled about the axle between one arm of the bracket, and the ribbon-carrying spool is adapted to hold the reel yieldingly against rotation. The spool 82 and ratchet-wheel 83 are fixed on the axle 79. The ink-ribbon 78 is wound upon these reels at its respective ends, and the ribbon is wound back and forth lengthwise by the rotating of these reels synchronously, whereby a fresh part of the ink-ribbon may be provided for the type at each impression.

For automatically moving the ink-ribbon mechanism is provided which engages alternately with one or the other of the ratchet-wheels 83 and is operated by the spacing mechanism, and consists of a shifting bar 84, supported movably in the bottom of the frame E and adapted to be reciprocated endwise by means of the thumb-piece 85, integral with the bar, two upright sleeves 86, fixed to or integral with the bar 84, one at each side of the frame E, adapted to receive and guide therein the vertically-moving pins 87, which pins are each provided with a spring-finger 88, adapted to engage with the adjacent ratchet-wheel 83 and with a rigid horizontally-extending arm 89, adapted to engage on the under side and receive the downward thrust of the spacing-arm 54, and a spring 90, coiled about the pin 87 between the top of the sleeve 86 and the arm 89,

adapted to hold the pin 87 yieldingly up to its highest position, carrying the finger 88 above the next tooth of the ratchet-wheel 83 when the arm 89 is released from the downward pressure of the spacing-arm 54. It will be understood that by each depression of the spacing-arm 54 through the mechanism just described one of the ratchet-wheels 83 will be rotated one notch and the ink-ribbon will be carried forward correspondingly. When the ink-ribbon has by this process been wound entirely on one of the reels by shifting the bar 84 toward the other side of the machine, the ratchet-wheel 83, theretofore in engagement with the spring-finger 88, will be released therefrom and the ratchet-wheel 83 at the other side of the machine will be brought into engagement with the spring-finger 88 on that side of the machine, whereby the movement of the reels will be reversed and the ink-ribbon will be rewound on the reel now in engagement with the spring-finger 88. The engagement of the ratchet-wheel 83 with the spring-finger 88 does not hinder the shifting of the ribbon on the reels by means of the cranks 80 when desired. The ribbon 78, as will be seen in Fig. 1, is held centrally in the fingers of the arm 76, and, as the arm 76 is reciprocated forward and back by the mechanism to which it is attached, the ink-ribbon, being flexible between the fingers 77 and the reels, is carried back and forth from and to the locality over the central point of type-impression at each thrust of a type, whereby the impression on the paper is uncovered, so far as the ribbon is concerned, immediately after it is made, and the operator thereby is able to see the impression produced immediately after the printing is performed, while the ribbon is returned to position in time to receive the impression of the succeeding type-stroke.

The bracket 45 I preferably construct in one piece cut from sheet metal and swaged in the form shown in Fig. 5. The end of the bracket 91 is turned over and reversed, forming bearings for the key-lever and its pivot, and the strip 92 cut from the body of the bracket is turned outwardly and backwardly 50 parallel with the face of the bracket, forming bearings for the type-bar and its trunnions, as shown in Fig. 10 in section on line Y Y of Fig. 4. The strip 92 is somewhat elastic, and is sprung out for inserting the trunnions 93 55 93 on the type-bar, and then springs back and is held in position adjustably by the set-screw 94 turning through it into the body of the bracket 45. A flange 95, also integral with the bracket 45, is adapted as a foot for securing the bracket on the supporting-frame E.

It will be understood that the paper or material to be printed upon is placed flat on the table D, and is secured thereto by the clip 25, and that the carriage C, with its table D and thereon-supported paper, is automatically carried from right to left intermittently below the type-bars at each depression of the spac-

ing-lever 54, either by the downward thrust on a letter-key or on the spacing-key, and the carriage is withdrawn toward the right by the hand taking hold most conveniently of the knob 96 on the crank 18, which knob and crank are also adapted, as hereinbefore described, for forcing the table D rearwardly by means of the pawl 19, engaging with the teeth 20, whereby the proper spacing of the lines is accomplished. It will also be understood that by means of the provision made for raising the key-blank frame E to some distance above the table D very thick material—such as a block of many sheets of paper or even a book—may be placed on the table D, beneath the frame E, and be printed upon.

Should it be desirable to use this machine for printing on very large or wide books, it is only necessary to make the bed-plate A sufficiently long laterally and the other parts of the machine correspondingly long or broad laterally to receive such book to adapt this machine for the widest and largest books, even such as are used for railroad or public records.

What I claim as new, and desire to secure by Letters Patent, is—

1. In a type-writing machine, the combination, with the main frame, of standards, one at each side, secured to the bed-plate, brackets supported and movable vertically on the standards and provided with means for raising and lowering them on the standards, and a key-bank frame supported on the movable brackets and so hinged or pivoted thereto as to be tiltable vertically, substantially as described. 95

2. In a type-writing machine, the combination, with the main frame, of standards, one at each side, pivoted to the bed-plate so as to be tiltable rearwardly thereon, each provided with a toothed rack in its vertical edge, brackets supported and movable vertically on the standards, pinions journaled and rotatable in the brackets, meshing with the racks on the standards, and a key-bank frame pivoted on the vertically-movable brackets so as to be tiltable upwardly and supported normally in a horizontal position thereon, substantially as described. 100 110 115

3. In a type-writing machine, a type-bar and key-lever supporting bracket 45, swaged from a single piece of sheet metal, having a turned-over end 91, forming bearings for the key-lever, and a reversed strip 92, forming bearings for the type-bar, substantially as described. 120

4. In a type-writing machine, an ink-ribbon wound upon reels supported at opposite sides of the key-carrying frame, which reels are provided with ratchet-wheels, in combination with a shifting-bar, two finger-carrying pins supported and movable vertically on the bar, springs whereby the pins are held yieldingly up to their work, the fingers being adapted one at a time to engage and pass intermittently a tooth on one of the ratchets 125 130

on the reels, and an arm rigid to the finger-carrying pins, adapted to receive and be depressed by the thrust of the spacing-arm of the machine, substantially as described.

5 5. In a type-writing machine, a flat paper-holding table provided with ratchet-teeth along one edge, the table being supported and adapted to travel in ways on a carriage of the machine, in combination with a bell-crank 18, pivoted to the carriage, a pawl 19, pivoted on one arm of the bell-crank, and an actuating-spring fixed in the arm of the bell-crank and bearing against a pin on the pawl, substantially as described.

15 6. In a type-writing machine, the combination of a swinging spacing-arm 54 and swinging parallel bars 56 and 57, to which spacing-arm 54 is pivoted, with a lever-arm 63, connected by a rod to one of the parallel bars 20 and provided with an upright 65, rocking lever 68, provided with rigid lever-arm 71, rocking shaft 8, provided with rigid lever-arm 73, connected by a rod to arm 71, and a dog 7,

pivoted on shaft 8 and adapted to engage alternately with ratchets on the carriage, substantially as described. 25

7. In a type-writing machine having a key-bank frame that is adjustable vertically on the frame of the machine, a rocking shaft 68, having its bearings in standards attached to the frame of the machine, an arm 67, rigid on shaft 68, and a slotted cam-lever 70, pivoted on arm 67, in combination with an upright 65, provided with a rack adapted to engage with arm 67, being held thereto and disengaged therefrom by cam-lever 70, the upright 65 being connected to a swinging arm of the spacing mechanism pivoted on the key-bank frame, substantially as described. 30 35

In testimony whereof I affix my signature in presence of two witnesses.

FRANK H. BOLTE.
